UNITED STATES PATENT OFFICE.

ELIJAH MCCOY, OF DETROIT, MICHIGAN, ASSIGNOR TO HENRY C. HODGES
AND CHARLES C. HODGES, OF SAME PLACE.

DOPE-CUP.

SPECIFICATION forming part of Letters Patent No. 460,215, dated September 29, 1891.

Application filed November 6, 1890. Serial No. 370,525. (No model.)

To all whom it may concern:

Be it known that I, ELIJAH MCCOY, a citizen of the United States, residing at Detroit, county of Wayne, State of Michigan, have invented a certain new and useful Improvement 5 in Dope-Cups; and I declare the following to be a full, clear, and exact description of the invention, such as will enable others skilled in the art to which it pertains to make 10 and use the same, reference being had to the accompanying drawings, which form a part of this specification.

It is the object of my invention to produce a dope-lubricator which will be simple in 15 construction and economical for use; and it consists of a combination of devices and appliances, hereinafter described and claimed.

In the drawings, Figure 1 is a vertical section of my cup. Fig. 2 is a side elevation of 20 the same.

In carrying out my invention, A represents the base of the cup adapted to be attached to the boxing or other part to be lubricated.

B is the body of the cup, screw-threaded at 25 its lower end to fit onto the base. Extending above the body is the neck or tube C.

D is a spindle, extending through this neck and down to the outlet-orifice a in the base. The end of the spindle is shaped to close this 30 orifice when the spindle is screwed down.

E is the piston working within the body and adapted to force the dope out through the outlet a, the piston being forced down by the spring E'. This piston is guided and 35 steadied in its movement by the guide-rods F, which extend from the piston up through the top of the body and are engaged to the collar G, which embraces the neck or tube C. Engaged to the upper end of the spindle is 40 the thumb-piece D', which is screw-threaded to fit into the upper end of the tube. This thumb-piece is provided with a projecting pin d. On the upper face of the collar G is a post or projection g, provided with the notch or 45 opening g' to receive the pin d. Now when the collar, and consequently the piston, is raised and the thumb-piece revolved the pin entering the notch holds the collar to its uppermost position until disengaged by revolving 50 the thumb-piece. So, also, by making the upper face of the notch g' rounding, as shown,

the collar cannot be disengaged except by slightly raising the collar and compressing the spring and then revolving the thumb-piece. Then, again, the length of the spindle 55 is so proportioned that where the thumb-piece and spindle are revolved to disengage the pin from the notch it forces the lower end of the spindle to its seat in the outlet-orifice and thus closes the outlet. Thus the piston 60 cannot be raised and locked up without first shutting off the outlet, and when it is desired to feed the dope the size of the outlet or the feed cannot be regulated until after the piston is unlocked.

Another material advantage is that when 65 the cup is empty the piston can be drawn up and locked and then the body unscrewed from the base, taken to the receptacle containing the supply of dope, filled, and returned to its base with the piston still locked up and out of the way.

What I claim is—

1. In a dope-cup lubricator, the combination, with the body provided with a tubular neck at its top and an outlet-orifice at its bottom, of a lengthwise-adjustable spindle moving in the tubular neck for opening and closing the outlet-orifice, an interior piston, and guide-rods extending from the piston 75 through the top of the body and engaged to a collar, said collar sliding on the tubular neck extending from the top of the body, substantially as described.

2. In a dope-cup, the combination, with the 85 body having a tubular neck at its top and an outlet-orifice at its bottom, of a spindle extending through the neck to open and close the outlet-orifice, and having an attached thumb-piece provided with a projecting pin 90 and in screw-threaded engagement with the neck, so that by turning the thumb-piece the spindle is raised or lowered, a piston in the body, and a guide for the piston having a collar provided with a notch for engaging the 95 pin on the thumb-piece which raises and lowers the spindle, so that by turning the thumb-piece the pin is disengaged from the notch and at the same time the spindle is moved to close the outlet-orifice, substantially 100 as described.

3. In a dope-cup, the combination, with the

- body having a tubular neck at its top and an outlet-orifice at its bottom, and a spindle moving in the neck and having a thumb-piece in screw-threaded engagement with the neck, of a piston in the body having a pair of guide-rods provided with a connecting-collar, and a pin-and-notch connection between the collar and the thumb-piece, which raises and lowers the spindle, substantially as described.
- 10 4. In a dope-cup, the combination of the spring-actuated piston and its guide-rods engaged to the collar G, the thumb-piece D',

provided with the spindle D, extending down to the outlet-orifice, and the pin and notched post for engaging the parts together, said spindle being of such length that when revolved to unlock it from the collar the outlet will be closed, substantially as described.

In testimony whereof I sign this specification in the presence of two witnesses.

ELIJAH MCCOY.
